PACKER

Richard E. Fulkerson, Coffeyville, Kans., assignor
to The Exner-Dodge Packer Company, Coffey-
ville, Kans., a corporation of Kansas

Application March 29, 1937, Serial No. 133,611

7 Claims. (Cl. 166—12)

This invention relates to packers, and particularly to those known as wall packers, used in packing off upper and lower portions of a well hole.

5 Packers of this character usually consist of a single unit, including a plurality of slips that are wedged against the wall of the well so that the packing element and pipe carried therefrom are dependent upon the slips for their support. For 10 this reason, packers of this character are not ordinarily used in open holes where there is no well casing, because the size and imperfect conditions of the open hole do not provide sufficient contact of the slips to support the weight and resist 15 thrusts imparted incidental to well operations. Owing to the fact that this type of packer can be set at a definite point, it is otherwise suitable for packing off upper and lower formations in an open hole, for example upper gas stratum 20 from a lower oil producing stratum, which are very close together. In this instance, the packing element must be accurately placed, and if necessary relocated until the packing is effectively positioned. However, even if the wall formation 25 is hard and round enough to provide sufficient grip for the slips, the shallow spacing between the formations to be separated frequently will not accommodate the length of the packer.

It is, therefore, a principal object of the present invention to provide a packer of this character 30 constructed so that the packing element may be located at the desired point in the well or open hole, with the slips or supporting mechanisms located within and gripping the inner face of the well casing at a point some distance above the packing element.

It is also an important object of the invention 35 to provide a packer construction of this character that is simple and relatively easy to set, and which may be readily released, to be raised or lowered, in case the desired packing action has not been attained with the first setting.

Other important objects are to effect substantially simultaneous setting of the supporting slips with the packing element; and to provide 40 the packer with means for effecting slidable seal with the tubing that is associated therewith.

In accomplishing these and other objects of the invention, as hereinafter pointed out, I have 45 provided improved details of structure, the preferred form of which is illustrated in the accompanying drawings, wherein:

Fig. 1 is a vertical section through a portion of an oil well equipped with a wall type packer embodying the features of the present invention.

Fig. 2 is an enlarged section through the well and slip end of the packer prior to setting of the slips with the well casing.

Fig. 3 is a similar view of the lower end of the packer before expanding of the packing element 5 into packing contact with the wall of the open hole.

Fig. 4 is a section similar to Fig. 2, but showing the slips in set condition and grippingly engaging the casing to support the packing element. 10

Fig. 5 is a section similar to Fig. 3, but showing the packing element in expanded condition and packingly engaging the wall of the open hole.

Fig. 6 is a cross-section on the line 6—6 of 15 Fig. 4.

Fig. 7 is a cross-section on the line 7—7 of Fig. 3, showing the lugs which control expansion of the packing elements in latched position.

Fig. 8 is a similar cross-section on the line 8—8 20 of Fig. 5, showing the lugs in unlatched position to effect expansion of the packing element.

Fig. 9 is a detail perspective view of the packing expanding control element.

Referring more in detail to the drawings: 25

I designates the bore hole of an oil well extending from the surface of the earth through a cap rock 2 into oil and gas producing formations 3 and 4 respectively, the formations 3 and 4 being separated by a non-producing formation 30 5 which may be of relatively shallow depth. The bore hole is cased above the cap rock 2 by the usual casing 6, having a shoe 7 supporting the weight thereof upon the cap rock, as in conventional practice. The bore hole extending below 35 the cap rock is uncased and known in oil field parlance as "open hole". In the instance illustrated, it is necessary to pack off the well between the formations 3 and 4 to control the flow of the gas separately from the oil, so that the 40 oil when discharged contains a minimum amount of gas, and the gas flow is free of entrained liquid. This necessitates that a packing be set within the formation 5 to separate the gas coming from the upper formation and keep it apart 45 from the oil being produced by the lower formation.

A conventional wall packer would be most convenient for this purpose, but as above pointed out, 50 the size and/or irregularity of the open hole, together with the crumbling nature of the formation, makes the use of slips difficult or entirely impracticable, and particularly where the formation 5 is so thin that it will not accommodate 55

the combined length of the packing element and slips.

In carrying out the present invention, I have provided a packer 8, including a packing element 9, that may be successfully expanded to packingly engage the formation 5, and which is sup- 5 portingly retained by slips 10 engaged within the casing 6, as now to be described.

The packer includes sections of tubing 11 and 10 12 on which the packing element and slip mounting members are respectively mounted for sliding movement thereon. The slip mounting member includes a section of pipe 13 of larger diameter than the tubing, and of sufficient length 15 to accommodate a slip carrying sleeve 14 that is freely slideable thereon. Formed on the upper end of the pipe 13 is a head 15 having an inverted frusto-conical slip engaging face 16 merging from the peripheral surface of the pipe to a cylindrical collar portion 17 having an axial opening 18 therein to slidably pass the tubing 11. The head 20 thus forms a wedging element adapted to enter the slips and force them outwardly into contact with the wall of the casing, as later described.

The slip carrying sleeve 14 is of smaller outer diameter than the inner diameter of the casing to accommodate drag springs 19 which comprise flat leaves having their lower ends welded or otherwise attached to the lower end of the sleeve, 25 as shown at 20, and which have their intermediate portions 21 bowed outwardly to frictionally drag upon the casing. The upper ends of the springs extend inwardly in the direction of the pipe 13 to guidingly bear thereupon through notches 22 30 that are formed in the upper end of the sleeve. The drag springs are arranged symmetrically about the periphery of the sleeve, and are of sufficient number to retain the packer centered within the casing. Welded to the sleeve, as indicated at 23, are resilient slip supporting reins 35 24, having their upper ends 25 projecting above the sleeve to support the slips 10, there being one slip attached to each of the reins.

Each slip 10 includes an arcuate segment of 40 sufficient width to cooperate with the other slips in forming a substantially continuous gripping surface circumferentially of the packer. The outer surfaces of the slips have wickers or teeth 45 26 to grip the casing, and the inner surfaces 27 conform to the taper of the head 15. The reins 24 have sufficient spring action to normally retain the slips in contracted position and against the pipe or lower end of the head so that they 50 will normally pass freely through the casing 55 without dragging thereon.

Secured to the lower end of the sleeve 14 in lapping relation with the pipe 13, are diametrically spaced hooks 28, each having downwardly converging side edges 29 and 30 forming triangular shaped ways 31 and 32 between the adjacent side edges of the hooks to guide diametrically arranged gudgeons 33 and 34 on the pipe 13 into lateral slots 35 of the hooks. The slots terminate in gudgeon seats or safety notches 37 60 that extend slightly below the lower edges thereof to accommodate the gudgeons when the hooks are engaged therewith, as later described.

The supporting means for the packing element 9 also includes a pipe section 38, conforming in 65 diameter to the pipe section 13, and of sufficient length to accommodate the packing element. The packing element 9 consists of a sleeve formed of resilient material and adapted to return to its original shape after being expanded into sealing contact with the well hole. The packing element

is sleeved over the pipe and the lower end 39 thereof abuts against a cap member 40, which is threaded upon the lower end of the pipe and carries a packing box 41 for passing the lower end of the tubing section 11.

In the illustrated instance, the packing box 41 has a packing chamber 42 containing resilient packing material 43 that is compressed against the tubing 11 by a packing gland 44. The packing gland 44 has a lateral flange 45 provided with openings 46 to pass the threaded ends of stud bolts 47 welded onto the cap member. The threaded ends of the stud bolts are provided with nuts 48, whereby the packing gland is drawn into contact with the sealing material to effect a sliding seal about the tubing. The upper end of the packing sleeve carries a collar or expanding ring 49, having a depending tubular portion 50 to which the packing sleeve is rigidly attached. The collar 49 is of suitable inner diameter to be 10 freely slideable on the pipe section 38, and is of outer diameter to substantially conform to the normal diameter of the packing sleeve, as best shown in Fig. 3. Formed in the inner surface of the collar is a circumferential groove 51. Formed in the wall of the pipe section 38 are bayonet slots 54 which have their upper portions 15 conforming in height to that of the groove. The narrow portions 55 of the slots are offset laterally from one side of the enlarged portions to leave 20 lug engaging shoulders 56 sloping upwardly toward the slot portions 55. Welded on the tubing 25 11 is a collar 57 having radial lugs 58 normally extending through the enlarged portions of the slots and into the annular groove 51. The lugs 30 are of sufficient width so that they may pass through the narrow portions 55 of the bayonet slots, and the slots are of sufficient length to allow ample movement of the lugs to effect expansion of the packing sleeve to the desired 35 diameter, as hereinafter described. For example, when the packing element is in contracted position, as shown in Fig. 3, the lugs 58 lie within the enlarged portion of the slots with the sloping lower edges 59 resting upon the shoulders 56. 40 When in this position, the lugs lock the tubing, the pipe section 38 and the packing element against relative longitudinal movement. However, when the tubing is rotated in a counter-clockwise direction (Fig. 7), the lugs 58 are moved 45 to bring them in registry with the narrow portions 55 of the slots, then when the tubing is moved downwardly relatively to the packing element, the lugs ride through the narrow portions 50 of the slots to press upon the collar 49 and effect 55 expansion of the packing element.

In order to assemble the parts just described the collar 49 is formed of upper and lower members 60 and 61 respectively, that are welded together, as at 62, after the lugs 58 have been inserted in the portion of the groove 51 that is carried in the lower section 61. The parts thus described are standard for packers embodying my invention, however, the spacing between the slips and the packing element must conform to the 65 conditions encountered in the well. This distance is determined by the location of the point to be packed, for example the formation 5, and the location in the casing at which the slips are to be set. When this distance has been determined, 70 sufficient tubing 63 is connected with the portions of tubing 11 and 12 by suitable couplings 64 and 65, as indicated in Figs. 2 and 3. Sufficient pipe 66, corresponding in diameter to the pipe sections 13 and 38, is inserted and coupled by means 75

of couplings 67 and 68 as shown in Fig. 1. When the correct length of tubing and pipe have been applied, the gudgeons 33 and 34 will be engaged with the safety notches 37 in the hooks 27 and 28 of the slip carrying sleeve 14, as shown in Fig. 2, and the lugs 58 will be engaged with the shoulders 56 in the enlarged portions of the bayonet slots as shown in Fig. 3. In these positions of the parts, the slips 10 are contracted about the lower end of the expanding head 15, and the packing element 9 forms a continuous cylinder between the collar 49 and the cap member 40 so that they do not interfere with running of the packer through the casing. The two body sections are thus joined together to make the whole device a single unit.

When using the packer, the entire unit is lowered into the well by means of the tubing until it has reached the desired setting point. This is accomplished by lengthening the tubing string in the usual manner. When the packing element has arrived at the desired setting point the tubing string is turned to the left, raising the tubing slightly while turning. This removes the gudgeons 33 and 34 from the safety notches 37 in the slots of the hooks. The drag or friction springs 19, acting upon the casing, retain the slip carrying sleeve 14 from radial or longitudinal movement, so that as soon as the gudgeons clear the slots 35, the pipe section 13, aided by the weight of the parts suspended from it, settles downwardly within the slip carrying sleeve 14 to bring the slip expanding head 15 into wedging engagement with the slips 10, thereby forcing them outwardly into gripping engagement with the wall of the casing. During rotation of the tubing, the lugs 58 are moved out of engagement with the stop shoulders 56, so that they then register with the narrow portions 55 of the slots. Therefore, further lowering of the tubing will cause the lugs 58 to move downwardly in the narrow portions of the slots, and since they engage against the bottom of the groove 51 in the collar 49, the downward pressure effects lateral expansion of the packing element against the wall of the well hole. During this movement of the tubing, it slides in the packing box 41 that is carried by the cap member 40 which has had its movement arrested upon engagement of the slips.

If, after setting of the packer, it is found that the packing element is set too high to effect the proper packing action, the tubing may be lifted until the lugs 58 again register with the enlarged portions of the bayonet slots 54, and the gudgeons 33 and 34 with the lateral slots 35 of the hooks 27 and 28 on the slip carrying sleeve 14. During this movement the lugs 58 engage the upper side of the groove 51 so that lift of the tubing effects elongation of the packing to its original length. The wedging head 15 has also been moved out of wedging engagement with the slips 10 to release them from the casing. Rotation of the pipe to the right will then cause the gudgeons to engage the safety notches 37 of the hooks and the lugs 58 to engage the large portions of the bayonet slots for seating on the shoulders 56. The tubing may then be set at a lower lever, as above described.

If the packer has been set at too high a level, the packing element and slips may be released merely by picking up the tubing and carrying the packer to a higher level and reset by slightly lowering the tubing, as above described.

From the foregoing it is obvious that I have provided a packer which is adapted to effectively

seal an open hole since the slip portion of the packer is firmly and securely anchored within the casing.

What I claim and desire to secure by Letters Patent is:

1. A packer including an upper tubular member, a slip carrier on the upper tubular member, slips on said slip carrier, a slip expanding head on the upper tubular member, means selectively connecting the upper tubular member with the slip carrier to prevent relative movement of the slip carrier with said tubular member, a lower tubular member having bayonet slots, a packing element sleeved on the lower tubular member and having one end anchoringly engaged with said lower tubular member, a setting ring connected with the other end of the packing element and having lug engaging portions, a tubing slidably through said tubular members, a collar on the tubing having lugs extending through the bayonet slots and into engagement with said lug engaging portions for latchingly connecting the tubing with said lower tubular member to normally prevent relative movement therewith, said tubing being rotatable in said members to release the slip carrier and said setting ring to effect setting of the slips and expansion of the packing element incidental to relative longitudinal movement of the tubing in said tubular members, and means on the slip carrier for preventing relative movement thereof incidental to movement of the tubing during setting of the slips and expansion of the packing element.

2. A packer including gripping means, a packing element, means connectingly suspending the packing element from the gripping means and having a bayonet slot, means connected with the suspending means for actuating the gripping means, means selectively connecting the gripping means with the connecting means to normally prevent actuation of the gripping means, a packer setting member, and a lug carried by the packing setting member and extending through said bayonet slot to connect with the packing element, said setting member being rotatably mounted to move said lug in the bayonet slot and effect disconnection of the gripping means with the suspending means for setting of the gripping means and expansion of the packing element.

3. In combination with a bore-hole having an upper cased portion and a lower uncased portion, a packer for packing off selected formation horizons with the uncased portion of the bore-hole including a tubular body of sufficient length to extend from a point in the cased portion of the bore-hole to a point in the uncased portion which is to be packed, casing gripping means on the upper end of said tubular body, means including a tubing extending through said tubular body for setting and releasing said casing gripping means for suspendingly supporting said tubular body in said cased portion, a packing element carried on the lower end of said tubular body, and means including said tubing for expanding and contracting said packing element to and from packing relation with the uncased portion of the bore-hole whereby the packer is adapted to be set and reset at different elevations in the bore-hole until the most effective location of the packing element is found with respect to said formation horizons.

4. In combination with a bore-hole having an upper cased portion and a lower uncased portion, a packer for packing off selected formation horizons within the uncased portion of the bore-hole

- including a tubular body of sufficient length to extend from a point in the cased portion of the bore-hole to a point to be packed in the uncased portion, casing gripping means on the upper end 5 of said tubular body, means including a tubing extending through said tubular body for setting and releasing said casing gripping means for suspendingly supporting said tubular body in said cased portion; a packing element carried on the 10 lower end of said tubular body, means including said tubing for expanding and contracting said packing element to and from packing relation with the uncased portion of the bore-hole whereby the packer is adapted to be set and reset at 15 different elevations in the bore-hole until the most effective location of the packing element is found with respect to said formation horizons, and a stuffing box carried by the lower end of the tubular body and sealingly engaging the 20 tubing.
5. In combination with a bore-hole having an upper cased portion and a lower uncased portion, a packer for packing off selected formation horizons within the uncased portion of the bore-hole, 25 including a tubular body of sufficient length to extend from a point in the cased portion of the bore-hole to a point to be packed in the uncased portion, casing gripping means adapted to be set incidental to movement of the tubular 30 body, an expandable packing element sleeved on the lower end of said tubular body and having one end anchored thereto, packing element expanding means slidably supported on the tubular body and connected with the opposite end of the 35 packing element, a tubing extending through said tubular body, packing means slidably sealing the lower end of the tubular body with said tubing, and means on said tubing having connection with said packing element expanding means and 40 latched engagement with said tubular body to rotate said tubular body in effecting connection and disconnection of said casing gripping means with said body to effect expansion and contraction of said casing gripping means to and from 45 gripping engagement with said cased portion incidental to reciprocation of the tubing with respect to the tubular body and for expanding and contracting said packing element to and from packing contact with the uncased portion of the 50 bore-hole, whereby the packer is adapted to be set and reset at different elevations in the bore-hole until the horizon to be packed has been located.
6. In combination with a bore-hole having an upper cased portion and a lower uncased portion, a packer for packing off selected formation horizons within the uncased portion of the bore-hole, including a tubular body of sufficient length to extend from a point in the cased portion of the bore-hole to a point to be packed in the uncased 55 portion, expandable casing gripping means sleeved on the upper end of said body, means fixed on said body for expanding said gripping means, means selectively interconnecting the casing gripping means with said body to prevent relative axial movement of said casing gripping

means with the tubular body when raising or lowering the packer in the bore-hole and releasable upon rotation of the tubular body in one direction, an expandable packing element sleeved on the lower end of said tubular body and having one end anchored thereto, packing element expanding means slidably supported on the tubular body and connected with the opposite end of the packing element, a tubing extending through said tubular body, packing means slidably sealing the lower end of the tubular body with said tubing, and means on said tubing having connection with said packing element expanding means and latched engagement with said tubular body to rotate said tubular body in effecting connection and disconnection of said casing gripping means with said body to effect expansion and contraction of said casing gripping means to and from gripping engagement with said cased portion incidental to reciprocation of the tubing with respect to the tubular body and for expanding and contracting said packing element to and from packing contact with the uncased portion of the bore-hole whereby the packer is adapted to be set and reset at different elevations in the bore-hole to locate the horizon to be packed. 10

7. In combination with a bore-hole having an upper cased portion and a lower uncased portion, a packer for packing off selected formation horizons within the uncased portion of the bore-hole, 15 including a tubular body of sufficient length to extend from a point in the cased portion of the bore-hole to a point to be packed in the uncased portion, expandable slips, a slip carrier sleeved on the upper end of said body, friction means on said slip carrier adapted to frictionally engage said cased portion, slip expanding means fixed on said body, means selectively interconnecting the slip carrier with said body to prevent relative axial movement of said slips with respect to the tubular body when raising or lowering the packer in the bore-hole and releasable upon rotation of the tubular body in one direction, an expandable packing element sleeved on the lower end of said tubular body and having one end anchored thereto, packing element expanding means slidably supported on the tubular body and connected with the opposite end of the packing element, a tubing extending through said tubular body, packing means slidably sealing the lower end of the tubular body with said tubing, and means on said tubing having connection with said packing element expanding means and latched engagement with said tubular body to rotate said tubular body in effecting connection and disconnection of said slip carrier with said body to effect movement of said slips to and from gripping engagement with said cased portion incidental to reciprocation of the tubing with respect to the tubular body and for radially expanding and contracting said packing element to and from packing contact with the uncased portion of the bore-hole, whereby the packer is adapted to be set and reset at different elevations in the bore-hole in locating the horizon to be packed. 20
